UNITED STATES PATENT OFFICE.

LAWRENCE R. BLACKMORE, GEORGE C. BLACKMORE, AND JOSEPH J. BLACKMORE, OF NEWARK, NEW JERSEY.

DESIGN FOR A RADIATOR.

SPECIFICATION forming part of Design No. 20,409, dated December 16, 1890.

Application filed September 9, 1890. Serial No. 364,490. Term of patent 7 years.

To all whom it may concern:

Be it known that we, LAWRENCE R. BLACKMORE and GEORGE C. BLACKMORE, citizens of the United States, and JOSEPH J. BLACKMORE, a subject of the Queen of Great Britain, all residing at Newark, Essex county, New Jersey, have invented a certain new and useful Design for Alternate-Loop Radiators, fully described and represented in the following specification and the accompanying drawing, forming a part of the same.

This design relates to the ornamentation of the loops of a radiator composed of vertical loops of uniform height in two alternate series with different patterns. Two or more loops of the same pattern may be grouped together to heighten the contrast between the alternate series.

The annexed drawing represents a radiator having the design applied thereto with alternating loops of a figured and a plain pattern.

are loops, shown herein arranged in pairs, ornamented by a continuous-figured pattern extending over the whole length of their ex-

posed faces, and bare loops of a plain pattern 25 ornamented in practice only with a tint of color or bronze, the two patterns of loops being arranged in alternate groups, the design thus presenting a strong contrast between the groups of figured and of plain pattern. 30

The groups of figured and plain loops produce by their difference in appearance a series of vertical columns, each of which forms a contrast with the adjacent column.

Having thus set forth the design, what we 35 claim is—

The design for a radiator herein shown and described.

In testimony whereof we have hereunto set our hands in the presence of two subscribing 40 witnesses.

LAWRENCE R. BLACKMORE.
GEORGE C. BLACKMORE.
JOSEPH J. BLACKMORE.
